United States Patent Office

Des. 227,750
Patented July 17, 1973

227,750

BOTTLE

Morton Goldsholl, Highland Park, Ill., assignor to Miles
Laboratories, Inc., Elkhart, Ind.

Filed Feb. 22, 1972, Ser. No. 228,441

Term of patent 14 years

Int. Cl. D9—01

U.S. Cl. D9—149

FIG. 1 is a perspective view of a bottle embodying my new design;

FIG. 2 is an elevational view;

FIG. 3 is an elevational view looking from the right of FIG. 2;

FIG. 4 is a sectional view taken along line 4—4 of FIG. 2; and

FIG. 5 is a bottom plan view thereof.

I claim:

The ornamental design for a bottle, substantially as shown.
